UNITED STATES PATENT OFFICE

OTTO KÜHNER, OF GÖPPINGEN, GERMANY, ASSIGNOR TO L. SCHÜLER A.-G., OF GÖPPINGEN, GERMANY, A CORPORATION

DRAWING PRESS

Application filed March 31, 1930, Serial No. 440,527, and in Germany April 12, 1929.

My invention relates to drawing presses and more particularly to pneumatic means connected with such presses for supporting the blank which are so designed that a duplex operation is performed on a single-acting press.

In presses of this type it has already been suggested to support the outer annular blank holder on a pneumatic piston which is fitted to slide on the rod of a second pneumatic piston, the second piston in turn supporting the inner annular blank holder. The drawing matrix as the ram descends and at first acts on the outer blank holder through the blank while the inner blank holder acts as the drawing punch, and the blank is cupped on the inner blank holder until a shoulder in the cavity of the matrix bears on the flange of the partly formed cup and the inner blank holder. The inner blank holder surrounds a fixed drawing punch which performs the final cupping operation.

In this system during the first stage of the operation the inner annular blank holder which acts as the drawing punch requires a pneumatic pressure which is much in excess of that required for the second stage so that for the second stage the compressed air supporting the inner annular blank holder must be partly discharged before the second stage is started, involving considerable loss of energy.

It is an object of my invention to eliminate this drawback. To this end I provide multiple means for supporting the inner annular blank holder and means operatively connected with the outer annular blank holder for partly cutting out such multiple supporting means at the end of the first stage.

In this manner the inner annular support is under sufficient pressure for the first stage while during the second stage the pressure is only that required for supporting the blank in such manner as to eliminate the formation of cracks in the blank.

In reducing my invention to practice I may provide three pneumatic pistons, one supporting the outer blank holder, and the other supporting the inner blank holder, while the third piston provides an additional

support for the inner blank holder, and means are provided for positively connecting the third piston with the ram of the press so that it is entrained by the ram and no longer acts as a support for the inner blank holder. 55

In a modification of my invention I provide two pistons only, one for the outer and one for the inner blank holder, insert a spring between the inner blank holder and its piston, and provide means for operating the spring together with the piston during the first stage, and alone during the second stage, after its supporting piston has been positively engaged by the ram, as described 60 with reference to the type with three pistons. 65

In the drawings affixed to this specification and forming part thereof a press having three pistons, and a press having two pistons and a spring, are illustrated diagrammatically by way of example. 70

In the drawings

Fig. 1 is an axial section of the three-piston press and the lower part of the ram with the matrix, and 75

Fig. 2 is an axial section of the two-piston press, the ram and the matrix being omitted.

Referring now to the drawings, *b* is the table of the press, *2* is a hollow support on the table, *a* is the fixed drawing punch in the support *2*, *c* is the inner, *d* is the outer annular blank holder, *x* is the fixed blanking ring which is secured in the support *2*, *11* is a cylinder which is held below the table *b* by any number of screws *15*, only one of which is shown, *f*, *f* and *r*, *r*, respectively, are push bars extending downwardly from the inner and outer blank holders *c* and *d*, respectively, and *t* is an annular slide which is secured on the ends of the rods *r*, *r* by 80 nuts *s*, *s*. 85

Referring now to Fig. 1, *7* is the ram of the press, *e* is a matrix which is secured at the lower end of the ram, *9* is a recess extending inwardly from the lower face of the ram, *y* is a shoulder at the end of the recess, and *10* is a spring-controlled piston which is inserted in the matrix so as normally to project slightly beyond the shoulder *y*. 95 100

The cylinder 11 is subdivided into three chambers *i*, *k* and *m*, each with a piston *q*, *p* and *n*, respectively, and with a pipe 12, 13 and 14, respectively, for connecting each chamber with an air vessel, not shown.

5 *h* is the rod of the lowermost piston *n* which projects upwards through the three compartments of the cylinder 11 and is provided with a washer *g* at its upper end on which the rods *f* of the inner blank holder *c* are abutted.

10 *o* is the hollow piston rod of the second piston *p* which extends through the partition between the chambers *i* and *k* and is fitted to slide in the uppermost piston *q*. *v* is a sleeve which is threaded on the upper end of the hollow piston rod *o* and is provided with a flange *u* at its lower end. The ring *t* to which the rods *r* from the outer blank holder *d* are secured by the nuts *s* is fitted to slide on the sleeve *v* and to cooperate with its flange *u*. The lower ends of the rods *r* extend beyond the ring *t* and the flange *u* and are supported on the uppermost piston *q* when the parts are in the initial position illustrated in Fig. 1.

15 In operation, when the ram *e* descends it bears on the blank which is supposed to be supported on the blanking ring *w* with its lower face *w* and depresses the inner blank holder *d* while separating the blank at *w*. The uppermost piston *q* descends with the blank holder *d* under the action of the rods *r* while air from the compartment *i* is forced back into the air vessel (not shown) through the pipe 12. The inner blank holder is supported by the pistons *p* and *n* until the ring *t* at the end of the rods *r* engages the flange *u* at the lower end of the sleeve *v*. Consequently, the inner blank holder *c* acts as the drawing punch for the cup which is formed in the blank during the first stage. The first stage is completed when the ring *t* engages the flange *u* of the sleeve *v* and moves downwardly the piston *p* through the medium of its hollow rod *o* on which the sleeve is secured. The rod *o* now releases the washer *g* at the lower end of rods *f* so that the inner blank holder *c* is only supported by the rod *h* of the lowermost piston *n* and moves down with the shoulder *y* of the matrix *e* while at the same time the piston *n* recedes into its cylinder. The second stage is now performed by cupping the blank on the fixed drawing punch *a*. During the descent of the pistons *p* and *n* the air from the respective compartments *k* and *m* is expelled through the pipes 13 and 14, respectively, into the air vessel (not shown).

20 When the ram *e* is reversed the compressed air from the air vessel flows back into the several compartments of the cylinder 11 and returns the pistons and the blank holders *c*, *d* into their respective initial position.

25 Referring now to Fig. 2, the intermediate

piston *p* and its compartment *k* in the cylinder 11 are dispensed with and only the compartments *i* and *m*, with their pistons *q* and *n*, are provided. The ends of the rods *r* abut on the upper face of the piston *q* as described, but the sleeve *v* is secured directly on the end of the solid rod *h* of the lowermost piston *n*. *z* is a cross head which is held between the rods *f* by suitable nuts *z'* and *F* is a spring which is inserted between the cross head *z* and the washer *g* at the end of the rod *h*. The rods *f* in this instance are free to move independently of the washer *g*. The ring *t* and the lower ends of the rods *r*, and the flange *u* at the lower end of the sleeve *v* are provided as described.

30 During the first stage only the upper piston *q* is lowered by the rods *r* of the outer blank holder *d* while the inner blank holder *c* is retained by the piston *n* and acts as the drawing punch for the blank during the first stage. At the end of the first stage the ring *t* engages the flange *u* on the sleeve *v* and moves down the piston *n* so that the second stage is performed only against the pressure of the spring *F* the initial pressure of which is adjusted by the nuts *z'* on the rods *f*.

35 The several adjusting facilities afforded by displacing the nuts *s*, *z*, and the sleeve *v*, serve for adapting the press to various conditions of operation, such as variations in the thickness of the blank and depth of cupping.

40 I wish it to be understood that I do not desire to be limited to the exact details of construction shown and described for obvious modifications will occur to a person skilled in the art.

45 In the claims affixed to this specification no selection of any particular modification of the invention is intended to the exclusion of other modifications thereof and the right to subsequently make claim to any modification not covered by these claims is expressly reserved.

50 I claim:—

55 1. A drawing press comprising a table, an outer annular blank holder and an inner annular blank holder, both fitted to slide with respect to said table, a fixed drawing punch on said table, a matrix adapted to cooperate with said holders and said punch, a cylinder disposed in a fixed position with respect to said table and having two compartments, a piston mounted to slide in the first compartment, a piston rod on said piston, means operatively connecting said piston rod to said inner blank holder, a piston mounted to slide in the second compartment and on said piston rod, and means operatively connecting said piston in the second compartment to said outer blank holder.

60 2. A drawing press comprising a table, an outer annular blank holder and an inner annular blank holder, both fitted to slide with respect to said table, a fixed drawing punch

on said table, a matrix adapted to cooperate with said holders and said punch, a cylinder disposed in a fixed position with respect to said table and having three compartments, a 5 first piston mounted to slide in the first compartment, a piston rod on said piston, means operatively connecting said piston rod to said inner blank holder, a second piston mounted to slide in the second compartment, a hollow 10 piston rod on said second piston which is mounted to slide on the piston rod of said first piston, a third piston arranged in the third compartment and mounted to slide on said hollow piston rod, means operatively 15 connecting said third piston to said outer blank holder, and means on said hollow piston rod for operatively connecting said outer blank holder to said second piston after said outer blank holder and said third piston have 20 moved through a given distance.

3. A drawing press comprising a table, an outer annular blank holder and an inner annular blank holder, both fitted to slide with respect to said table, a fixed drawing punch 25 on said table, a matrix adapted to cooperate with said holders and said punch, a cylinder disposed in a fixed position with respect to said table and having three compartments, a first piston mounted to slide in the first compartment, a piston rod on said piston, means operatively connecting said piston rod to said inner blank holder, a second piston mounted to slide in the second compartment, a hollow 30 piston rod on said second piston which is mounted to slide on the piston rod of said first piston, a third piston arranged in the third compartment and mounted to slide on said hollow piston rod, means operatively 35 connecting said third piston to said outer blank holder, and a check on said hollow piston rod which check is so positioned as to be engaged by said means for connecting said outer blank holder to said second piston only 40 after said outer blank holder and said third piston have moved through a given distance.

4. A drawing press comprising a table, an outer annular blank holder and an inner annular blank holder, both fitted to slide with respect to said table, a fixed drawing punch 45 on said table, a matrix adapted to cooperate with said holders and said punch, a cylinder disposed in a fixed position with respect to said table and having two compartments, a piston mounted to slide in the first compartment, a piston rod on said piston, means including a spring operatively connecting said piston rod to said inner blank holder, a piston mounted to slide in the second compartment and on said piston rod, and means operatively 50 connecting said piston in the second compartment to said outer blank holder.

In testimony whereof I affix my signature.

OTTO KÜHNER.
